UNITED STATES PATENT OFFICE.

PETRO TRARARA, OF BENTON HARBOR, MICHIGAN.

DESIGN FOR A WRITING SET.

Application filed December 13, 1924. Serial No. 11,695. Term of patent 14 years.

To all whom it may concern:

Be it known that I, PETRO TRARARA, a subject of the King of Italy, residing at Benton Harbor, in the county of Berrien and State of Michigan, have invented a new, original, and ornamental Design for Writing Set, of which the following is a specification, reference being had to the accompanying drawing, forming a part thereof.

The figure is a view in perspective of a writing set, showing my new design.

I claim:

The ornamental design for a writing set, as shown.

PETRO TRARARA.
